(57) **CLAIM**

The ornamental design for a beanbag-mounted tray and cup holder as shown and described.

DESCRIPTION

FIG. 1 is a front, right perspective view of the first embodiment of beanbag-mounted tray and cup holder.

FIG. 2 is a front, left, perspective view thereof;

FIG. 3 is a right side view, the left side view being a mirror image thereof;

FIG. 4 is a front view, the rear view being a mirror image thereof;

FIG. 5 is a top view thereof;

FIG. 6 is a bottom view thereof;

FIG. 7 is a front, right perspective view of the second embodiment of a beanbag-mounted tray and cup holder.

FIG. 8 is a front, left, perspective view thereof;

FIG. 9 is a right side view, the left side view being a mirror image thereof;

FIG. 10 is a front view, the rear view being a mirror image thereof;

FIG. 11 is a top view thereof; and,

FIG. 12 is a bottom view thereof.

The broken lines are for environmental purposes only and form no part of the claimed design.

1 Claim, 10 Drawing Sheets
